WRITING INSTRUMENT

Nolan K. Rhoades, Beloit, Wis., assignor to The Parker Pen Company, Janesville, Wis., a corporation of Wisconsin

Filed Nov. 1, 1962, Ser. No. 72,346

Term of patent 14 years

(Cl. D74—17)

The essential features of my design reside in the portions shown in solid lines on the drawing.

I claim:

The ornamental design for a writing instrument, as shown and described.
